APPARATUS FOR COATING MATERIAL

Roger C. Lawrence, Ridgewood, N. J., assignor, by
mesne assignments, to Western Electric Com-
pany, Incorporated, New York, N. Y., a corpo-
ration of New York

Application September 8, 1934, Serial No. 743,181

10 Claims. (CL 91—59.4,

This invention relates to an apparatus for coating material and more particularly to a nozzle for steam wiping strip or sheet material while advanced longitudinally.

5 The object of the invention is to provide an improved nozzle for applying steam or other gas to coated material.

In one embodiment of the present invention a nozzle is mounted to receive and direct a gas longitudinally of material while advancing from a 10 coating bath for removing excess coating therefrom, said nozzle having portions relatively movable to condition the nozzle for materials differing in width and thickness.

15 The invention will be more fully understood from the following description taken in connection with the accompanying drawing, wherein

Fig. 1 is a vertical sectional view of the nozzle mounted in a casing for receiving material from 20 a coating bath;

Fig. 2 is a sectional view taken substantially along the line 2—2 of Fig. 1 showing one form of 25 adjusting means;

Fig. 3 is a fragmentary sectional view taken 25 along the line 3—3 of Fig. 2, and

Fig. 4 is a fragmentary sectional view showing another form of adjusting means.

Referring now to the drawing, wherein like reference numerals designate similar parts throughout the view, numeral 10 designates a fixed portion 30 of a nozzle which portion is U-shaped in general contour, the side walls extending upwardly therefrom as indicated in Fig. 2 by reference numerals 11 and 12. Mounted upon the 35 side walls 11 and 12 of the fixed nozzle portion 10 is a supporting top 13 having a plurality of apertures therein for receiving upper ends of adjusting screws 14 as illustrated in Fig. 1. The 40 threaded ends of the adjusting screws 14 are receivable in threaded apertures of a movable nozzle portion 16. Set screws 15 carried by the supporting top and having their inner ends engaging lugs of the movable nozzle portion cooperate 45 with the adjusting screws 14 to lock the movable nozzle portion 16 in adjusted position. The 50 movable nozzle portion is similar in general contour to the fixed nozzle portion 10 with the exception that it is not provided with side walls as is the latter, but is slidably disposed between the 55 side walls 11 and 12 where it may be moved by the adjustment of the screws 14 and 15. Adjacent the center of the nozzle portions 10 and 16, their facing surfaces form a throat 18 for the 60 nozzle which surfaces gradually taper outwardly away from each other as they approach the outlet left end 19 of the nozzle. The walls of the nozzle portions 10 and 16 also taper outwardly from the throat 18 to the right thereof as illustrated in Fig. 1 forming walls of gas chambers 20 and 21 respectively. The right hand ends of the

nozzle portions 10 and 16 are turned inwardly and have secured thereto directing elements 22 of the cross-sectional contour shown in Fig. 1, which elements extend into the nozzle and terminate in edges 23 positioned short distances from the throat 18. The adjacent surfaces of the elements 22 are parallel with each other for a short distance, extending from the edges 23 to the right to form a passageway for a strip of material 25 to pass.

10 Positioned between the elements 22 and the adjacent surfaces of their respective nozzle portions 10 and 16 are spacing members 26 disposed at spaced positions along the inner edges of the elements, as illustrated in Figs. 1 and 2, to assure 15 the proper passageway between the chambers 20 and 21 and the throat 18 of the nozzle. These spacing members are somewhat elliptical in cross-section, giving them a stream-lined formation so as to cause the least disturbance possible to the 20 gas, which, as hereinafter described, is forced from conduits 27 and 28 into and through the chambers 20 and 21, respectively, through the throat 18 of the nozzle and through the passageway leading to the outlet end 19 of the nozzle. 25 The inner ends of the elements 22 are held against the spacing members 26 by screws, as illustrated in Figs. 1 and 2.

The side walls 11 and 12 of the fixed nozzle portion 10 taper outwardly as illustrated in Fig. 2 30 and the point where the taper begins constitutes a portion of the throat 18 of the nozzle in that it forms the sides thereof. The side walls 11 and 12 seal the ends of the chambers 20 and 21 and although the nozzle portion 16 is movable relative to the side walls, the ends of the chambers 35 remain sealed regardless of the position into which the nozzle portion 16 is moved.

In Figs. 2 and 3 an adjustable element is illustrated for conditioning the nozzle to receive strips of material of any desired width, the adjustable element consisting of an arm 31 having longitudinal projections 32 disposed upon each side of a longitudinal extending groove and arranged to extend between the inner edges 23 of the elements 22 and the adjacent portions of the nozzle members 10 and 16 to close the passageway between the chambers 20 and 21 and the throat 18 of the nozzle for a desired distance. The inner edges 23 of the elements 22 are receivable in the groove 40 of the arm 31, as illustrated in Fig. 3. A partitioning portion 33 of the adjustable element extends in a plane parallel to the tapered portion of the side wall 12 and has a contour corresponding to the surface contour of portions 10 and 16. 45 An adjusting screw 34 is rotatably mounted in the partition 33. A guide arm 35 integral with the partitioning member 33 extends parallel with the arm 31 through a cutaway portion in the wall 12 to assist in holding the adjusting element 50 55 60

against displacement and to assist in the movement of the adjusting member by the rotation of the screw 34. The arms 31 and 35 not only extend through the side wall 12 but through the adjacent wall of a casing 39 in which the nozzle is disposed. The adjusting screw 34 also extends through the wall 12 and through a threaded aperture in the wall of the casing 39 (Fig. 2). The wall of the casing 39 adjacent the supporting top 13 has apertures positioned in alignment with the adjusting screws 14 and the set screws 15 to permit adjustment of the nozzle portion 16 without removing the nozzle from the casing.

As shown in Fig. 3 the upper portion 16 of the nozzle is lowered into engagement with the partitioning member comprising elements 32, 33 and 35. For coating thicker sheets a thicker partition may be substituted for the one shown, although this is not in all cases essential as a small separation between the portion 16 and the element 32 will only result in a slight loss of steam and will not interfere with the wiping operation.

The adjustable nozzle is mounted in the casing 39 and removably held in place by any suitable means (not shown). Suitable insulating packing 40 may be disposed at spaces between the nozzle and the casing 39 and between the adjustable nozzle portion 16 and the supporting top 13 (Fig. 1). The casing 39 is mounted upon a tank 41 and has its open or lower end positioned beneath the upper surface of a coating bath 42, the casing serving as a separating chamber for the gas and the coating material during the final wiping operation. A door 43 hingedly secured to the casing 39 and constituting a part thereof has a recessed portion in the lower surface thereof cooperating with a recessed portion in the upper surface of a fixed horizontally extending element 44 for forming a wiping die 45. The fixed element 44 has its ends secured to projections 46 of the casing 39 and at each side of the wiping die 45 are positioned cam latches 47 for holding the door 43 in any desired adjusted position determined by the positions of adjusting screws 49, the latter serving as means to vary the size of the opening of the wiping die 45. The hinge connection for the door may be constructed so as to allow this movement to take place either by having the hinge connection loose as shown or having the apertures of the door which receives the hinge pin elongated. The location of the hinge makes it possible to swing the door upwardly into a position so that an operator may freely adjust the screws 14 and 15.

In the present embodiment of the invention which contemplates coating metal sheets with tin, zinc, or the like, one form of gas which may be utilized in the adjustable nozzle for the final wiping operation may be superheated steam which is passed through the nozzle at a pressure greater than atmospheric pressure. The material 25 upon passing from the bath 42 of coating material passes through the wiping die 45 where a quantity of the excess coating material is removed, the remainder of the excess coating material being removed as the strip of material 25 passes through the steam wiping nozzle. During the passing of the coated material through the nozzle, the superheated steam which is sent to the nozzle through the conduits 27 and 28 passes through the chambers 20 and 21 and enters the throat 18 of the nozzle completely surrounding the coating material and moves through the nozzle in a direction opposite the travel of the coated material to remove the remainder of the

excess coating material therefrom from the throat 18 of the nozzle to the inner end 19 thereof. The velocity of the steam increases due to its expansion so that the coated material is subjected to a wiping action by the movement of the steam at a high velocity longitudinally thereof for a substantial distance. The remainder of the excess coating material which is removed by this steam wiping operation is broken up into particles which are separated from the steam by gravity 10 in the casing 39 and returned to the bath 42. The spent steam passes from the casing into a laterally and upwardly extending exhaust pipe 60. The thickness of the coating material remaining on the coated sheet of material 25 may be controlled by varying either the speed of the coated material or the pressure of the steam or both, the higher speed tending to produce a heavier coating while a higher steam pressure or temperature tends to produce a lighter coating. 20

In the present embodiment of the invention, a sheet of material is shown being coated. An important feature of the present invention is that the nozzle may be adjusted to condition it to receive sheets of material not only of various widths but of various thicknesses. If it is desired to condition the nozzle to receive a sheet of material of greater thickness, the adjusting screws 14 are rotated to move the movable portion 16 of the nozzle away from the fixed portion 10 thereof to increase the vertical dimensions of the passageways in the nozzle. The nozzle may also be adjusted to receive strips of material of different widths by rotating the adjusting screw 34 (Fig. 2) to move the member 33 to a desired 35 location with respect to the side wall 11 to obtain the desired active width of the nozzle. Furthermore, as above indicated, one of a plurality of sets of these units may be employed, depending upon the thickness of the material being coated. 40

The form of adjusting means shown in Fig. 4 comprises a wedge shaped element 55 having its upper and lower surfaces extending angularly with respect to each other to engage the adjacent surfaces of the nozzle portions 10 and 16 45 and its side walls parallel to each other but extending at like angles from its front wall to conform to the taper of side wall 12 of the nozzle in advance of the throat 18. When the element 55 is disposed in place, its inner or rear wall 50 abuts the edges 23 of the elements 22 or extends between these elements, the element 55 being held in place by a clamp 56, the inwardly projecting ends of which engage outwardly projecting flanges 57 of the nozzle portions 10 and 55 16. A set screw 58, carried by the clamp 56 and constituting a part thereof, is positioned to engage the element 55 and force it into the position shown in Fig. 4, thus sealing portions of the chambers 20 and 21 and reducing the effective 60 width of the nozzle to the size desired. Due to the wedge shape of the element 55, one size may be used for more than one gage of material 25, whereas different sizes may be used for different widths of material. 65

What is claimed is:

1. In an apparatus for removing excess liquid coating from material while advancing from a liquid bath, a nozzle having nozzle portions forming a passageway therein through which the 70 coated material may pass, means in said nozzle portions for directing a gas under pressure through a portion of the passageway around the material to remove the excess liquid coating therefrom, one of said nozzle portions being 75

movable relative to the other for varying the size of the passageway through the said nozzle, and means for moving said nozzle portion perpendicularly to the path of said advancing material to maintain the same relation between the nozzle portion and the material.

5 2. In an apparatus for removing excess liquid coating from material while advancing from a liquid bath, a nozzle having nozzle portions 10 forming a passageway therein through which the coated material may pass, means in said nozzle portions for directing a gas under pressure through a portion of the passageway around the material to remove the excess liquid coating 15 therefrom, and means for moving one of said nozzle portions relative to the other in a direction perpendicular to the path of the advancing material for varying the size of the passageway through said nozzle.

20 3. In an apparatus for removing excess liquid coating from material while advancing from a liquid bath, a nozzle having nozzle portions forming a passageway therein through which the coated material may pass, means in said nozzle 25 portions for directing a gas under pressure through a portion of the passageway around the material to remove the excess liquid coating therefrom, movable means disposed in said passageway for varying the size thereof, and means 30 for moving said movable means in a direction perpendicular to the path of the advancing material.

35 4. In an apparatus for removing excess liquid coating from material while advancing from a liquid bath, a nozzle having a passageway therein through which the coated material may pass and comprising relatively movable elements supported and guided for relative movement in a rectilinear direction, and means for moving relatively said elements in a rectilinear direction for varying the size of the passageway in said nozzle.

40 5. A nozzle for receiving a material having a liquid coating thereon comprising nozzle portions having their inner surfaces formed to provide a passageway for the coated material, a gas compartment formed in each of said nozzle portions having their outlets positioned adjacent said passageway for directing gas under pressure therethrough during movement of the material for removing excess liquid coating therefrom, and means for varying the relative positions in a rectilinear direction of said nozzle portions for varying the size of the passageway through said nozzle.

45 6. A nozzle for receiving a material having a liquid coating thereon comprising nozzle portions having their inner surfaces formed to provide a passageway for the coated material, a gas compartment formed in each of said nozzle portions having their outlets positioned adjacent said passageway for directing gas under pressure therethrough during movement of the material for removing excess liquid coating therefrom, and means for varying the relative positions in a rectilinear direction of the nozzle portions for varying the size of the passageway in said nozzle to compensate for variations in thickness of coated materials to be advanced therethrough.

50 7. A nozzle for receiving a material having a liquid coating thereon comprising nozzle por-

tions having their inner surfaces formed to provide a passageway for the coated material, gas compartments formed in said nozzle portions having their outlets positioned adjacent said passageway for directing gas under pressure therethrough during movement of the material for removing excess liquid coating therefrom, means for varying the relative positions of the nozzle portions for varying the size of the passageway in said nozzle to compensate for variations in thickness of coated materials to be advanced therethrough, and a movable element disposed between the nozzle portions for varying the size of the passageway in accordance with variations in the widths of materials advanced therethrough.

5 8. A nozzle for receiving material advanced longitudinally from a liquid bath comprising a nozzle portion having a base wall and side walls extending substantially at right angles thereto, a movable nozzle portion disposed between said side walls, means for moving said movable nozzle portion relative to the other nozzle portion perpendicular to the path of movement of the advancing material for varying the size of the passageway formed between said nozzle portions, and chambers formed in said nozzle portions for receiving gas under pressure and having their outlets positioned to direct the gas through the passageway around the material for removing the excess liquid coating therefrom.

10 9. In an apparatus for removing excess liquid coating from material while advancing from a liquid bath, a nozzle having nozzle portions forming a passageway therein through which the coated material may pass, one of said nozzle portions having a base wall and side walls extending substantially at right angles thereto, the other of said nozzle portions being movably disposed between said side walls and guided thereby, means for moving said movable nozzle portion relative to the other nozzle portion for varying the size of the passageway in said nozzle in accordance with variations in thickness of coated materials advanced therethrough, means 15 in said nozzle portions for directing a gas under pressure therethrough during movement of the material for removing excess liquid coating therefrom, and means supported in one of said side walls and disposed in said passageway for varying the size of the passageway in accordance with variations in the widths of coated materials advanced therethrough.

20 10. A nozzle for receiving a material having a liquid coating thereon comprising nozzle portions having their inner surfaces formed to provide a passageway for the coated material, means in said nozzle portions for directing a gas under pressure therethrough during movement of the material for removing excess liquid coating therefrom, means for varying the relative positions of the nozzle portions for varying the size of the passageway in said nozzle to accommodate material of different thicknesses to be advanced therethrough, and movable means disposed between the nozzle portions for varying the size of the passageway in accordance with variations in the widths of materials advanced therethrough.
